(57) **CLAIM**

The ornamental design for a universal height absorbing toilet seal, as shown and described.

DESCRIPTION

FIG. 1 is a top perspective view of a first embodiment of a universal height absorbing toilet seal;

FIG. 2 is a front view of the universal height absorbing toilet seal shown in FIG. 1;

FIG. 3 is a back view of the universal height absorbing toilet seal shown in FIG. 1;

FIG. 4 is a side view of the universal height absorbing toilet seal shown in FIG. 1;

FIG. 5 is an opposite side view of the universal height absorbing toilet seal shown in FIG. 1;

FIG. 6 is a top view of the universal height absorbing toilet seal shown in FIG. 1;

FIG. 7 is a bottom view of the universal height absorbing toilet seal shown in FIG. 1;

FIG. 8 is a bottom perspective view of the universal height absorbing toilet seal shown in FIG. 1;

FIG. 9 is a top perspective view of a second embodiment of a universal height absorbing toilet seal;

FIG. 10 is a front view of the universal height absorbing toilet seal shown in FIG. 9;

FIG. 11 is a back view of the universal height absorbing toilet seal shown in FIG. 9;

FIG. 12 is a side view of the universal height absorbing toilet seal shown in FIG. 9;

FIG. 13 is an opposite side view of the universal height absorbing toilet seal shown in FIG. 9;

FIG. 14 is a top view of the universal height absorbing toilet seal shown in FIG. 9;

FIG. 15 is a bottom view of the universal height absorbing toilet seal shown in FIG. 9; and,

FIG. 16 is a bottom perspective view of the universal height absorbing toilet seal shown in FIG. 9.
